UNITED STATES PATENT OFFICE.

JAKOB SCHWEIZER, OF SOLEURE, SWITZERLAND.

GAS-MOTOR ENGINE.

SPECIFICATION forming part of Letters Patent No. 292,864, dated February 5, 1884.

Application filed March 2, 1883. (No model.) Patented in France January 16, 1883, No. 153,134.

To all whom it may concern:

Be it known that I, JAKOB SCHWEIZER, a citizen of the Republic of Switzerland, and a resident of Soleure, Switzerland, have invented certain Improvements in Gas Motors or Engines, of which the following is a specification.

My invention relates to an engine the piston of which is actuated by compressed aeron 10 form gases produced by intermittent explosions of a detonating mixture of gas and atmospheric air, the gases being compressed in the cylinder or closed vessel where the explosion takes place, and by their elastic tension 15 expanding directly into the cylinder of the engine through a valved aperture. The engine is "single-acting," so-called, and the valves which control the admission of gas to the vessel wherein the explosion takes place 20 and the escape of air from the engine-cylinder on its return-stroke are both actuated from the engine-shaft.

My object is to avoid the difficulty always encountered in gas-engines of getting rid of the 25 products of combustion, or "burned gases," so-called. I do this by separating my engine-cylinder from the explosion-chamber by an automatic check-valve which opens into the engine-cylinder. I explode my charge of 30 mixed gases in the upper part of the explosion-chamber, the lower part of which is filled with the heavier products of combustion. This compresses the latter and forces them downward through the valve-aperture into the engine-cylinder, where they act upon the 35 piston in the same manner as compressed air. The piston expels them at the next stroke. Thus each explosion expels into the engine-cylinder the burned gases left from the last preceding explosion. I interpose no piston between the supernatant explosive charge and the 40 heavier body of burned gases to be compressed.

In the drawings which serve to illustrate my invention, Figure 1 is a side elevation of my 45 motor, the water-jacket being partly broken away. Fig. 2 is a plan. Fig. 3 is a vertical section on line 33 in Fig. 2.

Let A represent a suitable bed-plate, and B a suitable frame mounted thereon, to support 50 the engine.

C is the engine-cylinder, surrounded by a water-jacket, D, to prevent undue heating.

E is the engine-piston, which is provided with the usual piston-rod, a, and cross-head b, arranged to reciprocate in guides in the frame 55 B. A connecting-rod, c, couples the cross-head b with a crank in the main shaft F, on which is mounted the fly-wheel G.

So far the parts described are similar to those of an ordinary single-acting engine. 60

Mounted on the top of the engine-cylinder C, so as to form a cover or head for the same, is a base-plate, d, which forms also the bottom of a closed cylinder, H, in which the detonating mixture is exploded, and in which the 65 products of combustion are compressed. This may be a closed vessel of any kind strong enough to stand the strain.

On the side of cylinder H is mounted a tubular piece, I, through which the gas passes 70 into the cylinder. Interiorly, the conduit or passage e in this piece communicates with a pipe, f, which turns upward in cylinder H, and is perforated at its upper end to permit the gas to escape into and diffuse itself in the upper part of H. The gas is admitted to the chamber H through a gas-pipe, g.

In the tubular piece I is a slide-valve, J, which has a cross-port that may, by the movement of said valve endwise, be put into or out 80 of register with the passage e, and thus control the admission of gas to cylinder H; and K is a slide-valve, also provided with a port, which is mounted to slide on the engine-cylinder and to control a port, h, in the latter, at 85 which the gas escapes from above the piston E when the latter rises. These two valves J and K are actuated by a valve-rod, i, common to both, which is reciprocated through the medium of a crank, eccentric, or cam, j, on the 90 main shaft F, whereby the admission of gas to H and the escape of gas from C are properly timed and regulated.

In the upper part of the cylinder H is an aperture, k, for the admission of air, which 95 aperture is closed by a check-valve, l, which opens inward. Opposite this aperture is a gas-jet, m, which is supplied with gas from the conduit e by a suitable pipe, as shown, and near this jet is another jet, n, supplied 100 from the same source. This is a relighting-jet, and its purpose will be explained more particularly hereinafter. The passage of gas through the conduit e may be regulated by a

cock, *o*, and that to the burners or jets by cocks *p*, as shown in Fig. 2.

I will now describe the operation. Suppose the valve *J* to be open to admit gas to the cylinder *H*, the piston *E* to be standing at the upper end of the cylinder *C*, and the valve *K* to be closed. The gas enters and mixes with the air in the upper part of cylinder *H* to an extent sufficient to form an explosive compound.

10 The jets *m* and *n* are lighted. The operator turns the fly-wheel *G* far enough to close the valve *J* and cut off the gas-conduit. The piston descends slightly and exhausts a portion of the air from cylinder *H* through a valved

15 aperture in *d*, which is closed by a valve, *q*, which opens downward and is normally upheld by a spring. The rarefaction of the air in *H* causes the outer air to rush into said cylinder at *k*, sucking in with it the flame from 20 the jet *m*. This causes an explosion of the gaseous mixture in the upper part of *H*, which simultaneously closes valve *l* and expands through the valve-aperture between *H* and *C*.

This effect is produced by the compression of 25 the gases in *H* due to the explosion, and the elastic tension of these gases acts upon the piston *E*, which thus receives a sufficient impetus to carry the crank in the main shaft over its center. When the piston has reached the 30 bottom of its outstroke, as in Fig. 3, the valve *K* opens port *h* and permits the compressed gases to escape, so that the piston may rise again. Thus, having once given the fly-wheel an impetus by hand, the explosions will take

35 place thereafter in rapid succession—one for each revolution of the main shaft—and the piston will receive a series of successive impulses, which will be sufficient to produce the required rotary motion of the shaft *F*.

40 It will be observed that the piston first acts to exhaust a portion of the gases from the cylinder *H*, whereby the flame of the jet is sucked or drawn in and the gases ignited, and is then acted upon itself by the elastic tension of the 45 gases compressed by the explosion. The sudden closing of the valve *l* by the explosion is apt to extinguish the jet *m*. Therefore I supply the relighting-jet *n*, which is so arranged as to relight jet *m*, but to be unaffected by the 50 shock of the valve when it closes.

I do not wish to limit myself to the precise construction and arrangement of the parts herein shown, as these may be departed from to some extent without detriment—as, for example, the valves *J* and *K* need not be actuated from the same valve-rod. It is only necessary that some good form of valve be employed, and that they be actuated at the proper time. The cylinder *H* and plate *d* might 55 also be in one. The jets *m* *n* might also be supplied with gas from some other point or source from that shown.

I have before stated that my object is to get rid of the burned gases. To accomplish this, 60 the rationale of my method is as follows: The chamber *H*, which is cut off from the en-

gine-cylinder, stands nearly full of the heavier products of combustion. A charge of an explosive mixture of lighter gases is introduced at the upper part of *H*, where they rest 70 or float on the heavier products of combustion below. The first part of the piston's descent slightly rarefies the gases in chamber *H*, and causes air to flow in at *k*, drawing in the flame of jet *m*. This ignites the charge, which 75 explodes and forces the gases in the lower part of *H*, down into the engine-cylinder, where they act on the piston. The piston, on its upstroke, expels the gases above it through *h*. Equilibrium has been re-established in *H*, and the same series of operations 80 is repeated.

It is designed that the air necessary to form the explosive mixture shall enter at *k*, as the valve *l* stands normally slightly ajar; but I 85 might admit an explosive mixture of inflammable gas and air through *f*, as is commonly practiced in gas-motor engines.

I am aware that it has been proposed to compress atmospheric air by means of a piston 90 acted upon by the explosion of a charge of detonating gases. This, however, differs materially from my method, as I employ no piston between the explosive charge and the gases to be compressed, and I compress the 95 burned gases left from the explosion of the last preceding charge. These gases pass into the engine-cylinder, and are exhausted therefrom without admixture with the next explosive charge.

Having thus described my invention, I claim—

1. In a gas-motor engine, the combination, with the vertically-arranged cylinder of the engine and the piston of the same, of a chamber, *H*, arranged on the top of the engine-cylinder, means for admitting a charge of a mixture of explosive gases to the upper part of said chamber, a valve, *l*, arranged to open into the upper part of said chamber to permit air to enter the latter, an automatic valve, *q*, in the partition separating the chamber *H* from the engine-cylinder, and arranged to open into said cylinder, a jet, *m*, arranged opposite to the valve *l*, and adapted to be drawn 105 into chamber *H* by the rarefaction of the gases in the latter, and means, substantially as shown, for admitting the explosive charge to the chamber *H*, whereby, when the charge explodes in the upper part of the chamber, the heavier products of combustion in the lower part of same will be compressed and forced 110 into the engine-cylinder, substantially as set forth.

2. The combination, in a gas motor or engine, of the engine-cylinder, piston-rod, piston, cross-head, connecting-rod, cranked-shaft, and fly-wheel, with the vessel *H*, provided with the valved air-inlet *k*, the valved aperture between it and the engine-cylinder, and the pipe *f*, the valve *J*, arranged to control the ingress of gas, the valve *K*, arranged to 115

control the exhaust-port of the engine-cylinder, means, substantially as described, for actuating said valves J and K, and the jet m, for igniting the gaseous mixture in the vessel H, 5 all arranged to operate substantially as set forth.

3. The combination, with the cylinder and piston of a gas-motor engine, of a closed chamber to receive an explosive mixture of air and 10 inflammable gas at its upper part, provided with an aperture or passage in its lower part leading into the engine-cylinder above the piston, a check-valve opening downward into the engine-cylinder to control said passage, an 15 aperture at the upper part of said explosion-chamber, and a check-valve to control said

aperture, arranged to open into said chamber, whereby when the charge is exploded it may force the heavier gases in the lower part of said chamber down into the engine-cylinder, 20 and whereby the rarefaction produced by the first portion of the downward stroke of the piston, prior to the explosion, may draw in the flame of the igniting-jet, substantially as set forth.

In witness whereof I have hereunto signed my name in the presence of two subscribing witnesses.

JAKOB SCHWEIZER.
